SURFACE FINISHING MACHINE

Albert H. Dall, Silverton, and Frank Esz, New-
town, Ohio, assignors to Cincinnati Grinders
Incorporated, Cincinnati, Ohio, a corporation
of Ohio

Application March 22, 1940, Serial No. 325,410

19 Claims. (CI. 51—157)

This invention relates to improvements in surface finishing machines and has particular reference to an improved machine for putting a final finish of high degree of accuracy on work pieces of hardened material.

One of the principal objects of the present invention is the provision of an improved machine, particularly adapted for simultaneous performance of finishing operations on a multiplicity of similar articles.

A further object of the present invention is the provision of a machine having the capacity of performing a finishing operation on the individual rolls of an anti-friction bearing subsequent to the assembly of the selected rolls for the bearing with the final individual cooperative race therefor.

A further object of the present invention is the provision of a machine for the purpose described of means for maintaining the individual bearings in a relationship to the associate rate corresponding to that which they will occupy under service conditions so that the finishing operation may best surface the bearing members for subsequent cooperation with the additional race unit in a manner to effect equalized load distribution on the bearing.

A further object of the invention is the provision of improved means for control of the several respective relative movements of the work pieces unitarily and as an entirety so that a proper relative scouring movement will be obtained during the finishing operation, eliminating the scratches and irregularities, or hill and valley effects, of the work incident to previous machining operations.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

In the drawings:

Figure 1 is a front elevation of a machine constructed in accordance with and embodying the principles of the present invention.

Figure 2 is a vertical sectional view thereof illustrating the relative position of the various parts during performance of a finishing operation—taken as on the line 2—2 of Figure 1.

Figure 3 is a transverse sectional view as on the line 3—3 of Figure 2.

Figure 4 is a similar sectional view on the line 4—4 of Figure 2.

Figure 5 is a plan view of the machine, certain of the parts being broken away or in section to indicate certain of the structural features common individually to the various units.

Figure 6 is a fragmentary plan view similar in character to Figure 5, illustrating the open or work receiving position of certain of the parts.

Figure 7 is a fragmentary vertical sectional view similar to Figure 2 illustrating the position occupied by the parts for removal or insertion of a work piece.

Figure 8 is a fragmentary sectional view of the tool release mechanism as on the line 8—8 of Figure 5.

Figure 9 is a section through the tool guide mechanism as on the line 9—9 of Figure 6.

Figure 10 is a diagrammatic view of the hydraulic system for supply of cutting medium and control of certain of the elements of the machine.

Figure 11 is a fragmentary sectional view similar to Figure 7 illustrating a modified form of work piece positioning means.

The present invention has been particularly illustrated as applied to the final finishing in situ of the taper rolls of a precision anti-friction bearing. It is a well-recognized fact that in normal production of anti-friction rolls of this character that they must be finished as accurately as possible to size by normal precision grinding operations, and subsequently, selection made of rolls of corresponding dimension within fine tolerances for assembly of such rolls in the ultimate individual bearing.

Conventional precision grinding machines, however, normally produce work having minute hills and valleys or irregularities, leaving what is known as a grinding fuzz on the work which ordinarily must be worn down by initial use before the rolls are finally seated in their races with maximum bearing area.

The present invention contemplates a final surfacing of the rolls or an individual bearing subsequent to assembly with its cooperating race for removal of this grinding fuzz so that the final bearing may be set up to desired tightness and will not require the ordinary care in the running-in operation or be subject to the liability of undesirable looseness or play which may otherwise result from the wearing down of the grinding fuzz after assembly of the bearing in its intended environment.

In the attainment of these results we have

shown in Figure 1 a finishing machine comprising a pedestal type base 15 having a supplemental pedestal section 16 providing a closed base 17 having rising therefrom an inner tubular portion 18 and an outer bell portion 19. These parts form therebetween a liquid receiving chamber 20 which, as will be noted, is entirely sealed off from the driving or actuating mechanisms contained in the chamber 21 provided in the lower portion of the pedestal 15. The portion 19 of the upper pedestal section has the peripheral flange 22 to which is suitably secured the circular bed plate 23 for support of the abrading media and the control mechanism therefor.

15 For support of a work piece in the machine there is journaled in the bearing bushings 24, interiorly fitted in the portion 18, a hollow vertical spindle 25 bearing at its upper end the expanding chuck or collet 26 adapted for inter-fitting engagement with the inner face of the bearing race 27. Expansion of this collet is effected by downward sliding movement thereof with respect to the frusto-conical wedge 28 extending upwardly from the cap 29 at the upper end of the spindle. Movement of the collet 26 for this purpose may be effected as by the draw-rod 30 slidable in the spindle and bearing at its lower end piston 31 contained within cylinder 32 hydraulically controlled by introduction and exhaust of suitable actuating medium under pressure through conduits 33 and 34.

35 By reference particularly to Figure 2 it will be noted that the spindle 25 has secured on the lower portion thereof the thrust bearing 35 having trunnions 36 engaged in links 37 pivoted as at 38 to the oscillating yoke 39. This yoke has its outer end rotatably secured to the column 15 as by the pivot 40 and has its inner end pivoted as at 41 to the rods 42 mounted as by 40 needle bearings 43 on the crank portions 44 of shaft 45. This shaft 45 is suitably journaled in the base 15 and bears on its outer end pulley 46 suitably driven as by belts 47.

45 From the foregoing it will be readily apparent that the rotation of shaft 45 will serve through the cranks 44 to impart a vertical oscillation to the yoke 39 and thus through the linkage described to the thrust bearing and spindle 25, causing a high speed reciprocation of the spindle. For this purpose the shaft 45 is preferably driven at a speed of approximately 900 revolutions per minute.

55 Centrally the shaft 45 is provided with a worm 48 meshing with worm gear 49 to effect relatively slow rotation of vertical shaft 50 which is journaled in suitable brackets 51 carried by the base 15. Keyed on the shaft 50 is a pinion 52 in driving engagement with gear 53 having a pinion portion 54, in turn driving gear 55 on 60 spindle 25. The reduction effected through the gear train just described is preferably of a nature to impart a slow speed such as 5 to 10 revolutions per minute to the work carrying spindle 25. It will thus be noted that the spindle has a compound movement including a high speed reciprocation coupled with a slow speed rotation, both of which movements will be imparted to the inner race 27.

70 For operation on the work piece, the table 23 has been provided with a multiplicity of sets of ways 56, preferably corresponding in number with the number of individual rolls in the bearing 27. These ways, as indicated in section in Figure 9, serve to guide the abrasive tool holders 75 57 as by the anti-friction bearings 58.

5 Springs 59 disposed in sockets 60 in the slides 57 react on the adjusting screws 61 carried by the upstanding flange 62 of the table for yieldingly urging the slides in the direction of the work piece to maintain the abrasive stones 63 in proper tensioned engagement with the rollers 21. It will be noted that these stones are mounted in holders 64 disposed between the furcations 65 at the end of the slide and supported in position as by the trunnions 66, permitting of longitudinal rocking of the abrasive members to permit them to accommodate themselves to the face angle of the rollers. At the same time the stones themselves are centrally grooved as at 67 to provide surface contact or engagement with the work. At the same time the grooved faces tend to restrain the rolls against bodily rotary movement with the result that the slow rotation of the inner race 27 will frictionally react on the rolls, giving each roll an independent rotary movement about its own axis so that its surface traverses the face of the inner or finishing member 63.

10 It is well known in the art that taper roller bearings of the type here particularly illustrated 15 are formed with a seat as at 68 for engagement with the base 69 of the roller. In assembly, however, there is a certain longitudinal clearance in the bearing seat or face 70 of the inner cone 27, the rolls being retained by conventional 20 cage such as 71. In order that the rolls during the high speed reciprocation of the drive spindle may at all times remain properly held against the seat 68, the spindle may be provided with an auxiliary roll retaining device such as illustrated, 25 for example, in Figures 7 and 11.

30 In the form shown in Figure 7 the cap 29 of the spindle is provided with a guide hub 72 on which the sleeve portion of collet 26 slides, while circumscribing the collet is a compressible spring 35 73 bearing at one end against the cap and at the opposite end against a sleeve 74 having a restricted axial movement relative to the collet as determined by engagement of screws 75 in groove 76 of the collet. This sleeve has an upper thin 40 rim 77 adapted for terminal engagement with the smaller ends of the rolls for yieldingly retaining the same against seat 68 as is particularly illustrated in connection with Figure 2.

45 An alternative structure for accomplishment of the same purpose has been indicated in Figure 11 in which in place of a single spring pressed sleeve adapted for simultaneous engagement with all of the work pieces there have been provided individual work engaging pins 78 upwardly resiliently urged as by springs 79.

55 For radially effecting control of position of the various tools or work abrading members, the several slides 57 have depending through slots 80 in the table lugs 81 on which are secured the 60 rollers 82, engageable by the cam portions 83 of the star wheel 84 rotatably mounted on hub 85 depending from the table 23. A rock arm 86 pivoted to piston rod 87 carrying piston 88 movable within cylinder 89 serves to actuate the star 65 wheel in a counterclockwise direction as indicated in Figure 6 to effect retraction of the several slides, or alternatively shifts the wheel in a clockwise direction to the position indicated in Figure 5 when the cams 83 are out of engagement with the rollers of the respective slides permitting the same automatically to position themselves in proper interengaging relation with the individual work pieces.

70 The general hydraulic control system for the 75

machine has been diagrammatically illustrated in Figure 10 from which it will be noted that there has been provided a tank or reservoir 90 from which the hydraulic actuating medium is drawn by a pump 91 which discharges into pressure conduit 92. One branch 93 of this conduit extends through automatic shutoff valve 94 and filter 95 to the coolant or cutting medium discharge nozzles 96. These nozzles are provided individual to the several tools, preferably being held by brackets 97 on the individual tool holding slides. The discharge coolant flows down past the work into the filter reservoir provided by the sliding guard 98 on spindle 25 interengaging with the filter media 99 in container 100 within the flange portion 19 of the column whence the same is collected in the receiving chamber 20.

During operation of the machine the hydraulic system is conditioned as indicated in Figure 10 with the stop valve 101 maintained in raised or opened position as by spring 102 so that pressure conduit 92 is connected through the valve with conduit 103 which has a first branch 104 causing pressure to react on valve 94, opening same for flow of coolant against the pressure of spring 105. Line 103, when under pressure, is additionally coupled by conduit 33 with piston 32 drawing down work holding collet 26 to clamp the work in position on the spindle. At the same time, pressure through conduit 106 and restricted passage 107 in valve block 108 introduces pressure against piston 88 to effect a slow or retarded clockwise movement of the star wheel permitting the various tool holding slides to move inward into engagement with the work.

At this time the opposite sides of pistons 32 and 88 are connected respectively through conduits 34, opened check valve 109 and common conduit 110 to valve 103 and thence through connection 111 to reservoir 90.

Shifting of valve 101 against its actuating spring 102 as by pressure on pedal 112 serves to reverse the pressure and exhaust connections, making 110—34 the pressure line and 33—106—103 the exhaust line. When this condition exists release of pressure in line 104 permits valve 94 to shift, automatically shutting off flow of coolant. At the same time pressure in conduit 110 immediately reacts to effect counterclockwise shifting of the star wheel and thus retraction of the work engaging tools. Pressure flow through restricted passage 113 into 34 effects a delayed raising of piston 32 for release of the work rest at a time subsequent to the retraction of the work engaging tools.

The foregoing description of the construction and operation of the machine should be readily understood and it will be noted that there has been provided an improved readily controlled machine in which a completely assembled inner bearing, race bearings and cage of an anti-friction bearing may be radially mounted, abrading tools quickly brought into engagement with the individual bearings and in which an effective compound relative movement of the abrading stones or tools and the individual work pieces may be readily effected in that a high speed reciprocation is imparted to the clamped bearing as an entirety, the slides automatically expanding and contracting with respect to each other to maintain a close interfitting engagement between the individual work pieces and the abrading tools.

Additionally, due to the slow rotation of the inner race and the radial pressure exerted by the abrading members the inner race will serve as

a regulating wheel effectively controlling and causing slow rotation of the individual bearings to their axes so that the respective tools will operate on all portions of the work surface in a series of closely related abrading paths extending substantially at right angles to the grinding lines or the effects produced by previous operations in the manufacture of the rollers, thereby tending to reduce the hill and valley effect and remove previously produced grinding fuzz.

It will, of course, be understood that for this purpose there is preferably employed an extremely fine abrading element, together with suitable coolant forming a film preventing unduly rapid cutting away of the work surface and at the same time suitably carrying away the metallic and abrasive particles loosened up by the process.

What is claimed is:

1. A machine for finishing the individual bearing elements of an anti-friction bearing for assembly, comprising a holder for engagement with the inner race of the bearing, a multiplicity of radially arranged abrading members individual to the individual bearing elements, means for yieldingly urging the abrading elements into engagement with said bearing elements, means for imparting high speed axial reciprocation to the bearing assembly as an entirety, and additional means for imparting a slow rotation to the inner bearing race whereby the same will act as a regulating wheel imparting a controlled uniform rotation to the individual bearing members with respect to the abrading element.

2. A machine for finishing the individual bearing elements of an anti-friction bearing for assembly, comprising a holder for engagement with the inner race of the bearing, a multiplicity of radially arranged abrading members individual to the individual bearing elements, means for yieldingly urging the abrading elements into engagement with said bearing elements, means for imparting high speed axial reciprocation to the bearing assembly as an entirety, additional means for imparting a slow rotation to the inner bearing race whereby the same will act as a regulating wheel imparting a controlled uniform rotation to the individual bearing members with respect to the abrading element, and means for preventing orbital movement of the individual bearing elements.

3. A machine for finishing the individual bearing elements of an anti-friction bearing for assembly, comprising a holder for engagement with the inner race of the bearing, a multiplicity of radially arranged abrading members individual to the individual bearing elements, means for yieldingly urging the abrading elements into engagement with said bearing elements, means for imparting high speed axial reciprocation to the bearing assembly as an entirety, additional means for imparting a slow rotation to the inner bearing race whereby the same will act as a regulating wheel imparting a controlled uniform rotation to the individual bearing members with respect to the abrading element, and supplemental means terminally engageable with the individual bearing elements for determining their axial position.

4. A finishing machine of the character described, including means for supporting an assembled anti-friction bearing, means for urging abrading members into engagement with the individual bearing elements, and means for effecting rotary and reciprocating relative move-

- ments of the bearing members and abrading means.
5. A machine of the character described including a support for an assembled anti-friction bearing embodying a plurality of bearing elements, means for resiliently urging an abrading member into engagement with one of said bearing elements, and means for imparting relative rotary and reciprocating movement to said bearing element and abrading member.
6. A machine of the character described, including a support for an assembled anti-friction bearing including a race and a plurality of bearing elements, means for supporting abrading tools adjacent the bearing in position for individual engagement with individual bearing elements, means for yieldingly maintaining the bearing elements and abrading members in operative engagement, means for effecting rotation of the bearing race at a slow rate of speed frictionally to control rotation of the individual bearing elements, and means for effecting a relative reciprocation at a higher rate of speed between the individual bearing elements and their abrading members.
7. A machine of the character described, including a support for an assembled anti-friction bearing including a race and a plurality of bearing elements, means for supporting abrading tools adjacent the bearing in position for individual engagement with individual bearing elements, means for yieldingly maintaining the bearing elements and abrading members in operative engagement, means for effecting rotation of the bearing race at a slow rate of speed frictionally to control rotation of the individual bearing elements, means for effecting a relative reciprocation at a higher rate of speed between the individual bearing elements and their abrading members, and supplemental positioning means engageable with the individual bearing elements for maintaining same in predetermined relation to their supporting race.
8. A machine of the character described, including a support for an assembled anti-friction bearing including a race and a plurality of bearing elements, means for supporting abrading tools adjacent the bearing in position for individual engagement with individual bearing elements, means for yieldingly maintaining the bearing elements and abrading members in operative engagement, means for effecting rotation of the bearing race at a slow rate of speed frictionally to control rotation of the individual bearing elements, means for effecting a relative reciprocation at a higher rate of speed between the individual bearing elements and their abrading members, supplemental positioning means engageable with the individual bearing elements for maintaining same in predetermined relation to their supporting race, and means for yieldingly maintaining said bearing element supporting means in effective position.
9. A machine for finishing of anti-friction bearings in assembled relation with respect to their supporting race, including a rotary spindle, means for securing the race to the spindle for rotation therewith, a plurality of tool supports radially disposed in circumscribing relation to the spindle, abrading elements carried by the supports and projectable for individual engagement with the bearing elements, and means for effecting relative movement between the race as an entirety and the abrading elements in a substantially axial direction as respects the spindle.
10. A machine for finishing of anti-friction bearings in assembled relation with respect to their supporting race, including a rotary spindle, means for securing the race to the spindle for rotation therewith, a plurality of tool supports radially disposed in circumscribing relation to the spindle, abrading elements carried by the supports and projectable for individual engagement with the bearing elements, means for effecting relative movement between the race as an entirety and the abrading elements in a substantially axial direction as respects the spindle, and means for resiliently maintaining the abrading elements in engagement with the bearing elements whereby constant interengagement of said elements is maintained during said relative reciprocating movement.
11. A machine for finishing of anti-friction bearings in assembled relation with respect to their supporting race, including a rotary spindle, means for securing the race to the spindle for rotation therewith, a plurality of tool supports radially disposed in circumscribing relation to the spindle, abrading elements carried by the supports and projectable for individual engagement with the bearing elements, means for effecting relative movement between the race as an entirety and the abrading elements in a substantially axial direction as respects the spindle, means for resiliently maintaining the abrading elements in engagement with the bearing elements whereby constant interengagement of said elements is maintained during said relative reciprocating movement.
12. A machine of the character described including a support for the inner race of an anti-friction bearing, means for effecting a slow speed rotation and a high speed reciprocating of said support, abrading members disposed in circumscribing relation to the support having portions for engagement with individual bearing members of an anti-friction bearing on the support, means for independently inwardly actuating said abrading members, and additional means for simultaneously retracting all of said abrading members to facilitate introduction and removal of a work piece.
13. A machine of the character described including a support for the inner race of an anti-friction bearing, means for effecting a slow speed rotation and a high speed reciprocating of said support, abrading members disposed in circumscribing relation to the support having portions for engagement with individual bearing members of an anti-friction bearing on the support, means for independently inwardly actuating said abrading members, additional means for simultaneously retracting all of said abrading members to facilitate introduction and removal of a work piece, means for supplying coolant to the abrading members when in work engaging position, a control for the retracting means, and coupled connections between said control and coolant supply for shutting off the flow of coolant on retraction of the abrading members.
14. A machine of the character described, including a supporting bed, a spindle supported thereby for rotary and reciprocating movements relative thereto, a drive shaft, eccentric means actuated by the drive shaft, operative connections between said means and the spindle for effecting reciprocation of the spindle, reduction gearing actuatable simultaneously with the eccentric means

by the driving shaft, and connections between said reduction gearing and said spindle for effecting rotation of the latter at an appreciably slower rate than the rate of reciprocation thereof.

5 15. A machine of the character described, including a supporting bed, a spindle supported thereby for rotary and reciprocating movements relative thereto, a drive shaft, eccentric means actuated by the drive shaft, operative connections 10 between said means and the spindle for effecting reciprocation of the spindle, reduction gearing actuatable simultaneously with the eccentric means by the driving shaft, connections between said reduction gearing and said spindle for effecting rotation of the latter at an appreciably slower rate 15 than the rate of reciprocation thereof, a head on said spindle, work holding means mounted on the head, and means supported by the bed in circumscribing relation to the work holding means 20 for operation on a work piece actuatable by the spindle.

16. A machine of the character described, including a table member having a plurality of radially extending ways, a work holder centrally disposed as respects said ways, tool holders slideable in the ways in a direction toward and from the work holder, work engaging tools carried thereby, means for yieldingly urging the respective tool holders in a direction toward the work holder, oscillatable cam means engageable with the tool holders for effecting retraction thereof, means for effecting a high speed relative axial reciprocation of the tool holder and the work holders, and additional means for effecting individual slow speed rotation of work pieces on the tool holder during said relative reciprocation of the parts.

17. A machine of the character described, including a table member having a plurality of radially extending ways, a work holder centrally disposed as respects said ways, tool holders slideable in the ways in a direction toward and from the work holder, work engaging tools carried thereby, means for yieldingly urging the respective tool holders in a direction toward the work holder, oscillatable cam means engageable with the tool holders for effecting retraction thereof, means for effecting a high speed relative axial re-

ciprocation of the tool holder and the work holders, and additional means for effecting individual slow speed rotation of work pieces on the tool holder during said relative reciprocation of the parts, said tools having portions interengageable with individual work pieces for preventing planetary movement thereof. 5

18. In a machine of the character described including a rotary work support, radially disposed tools disposed in circumscribing relation to the work support, means for yieldingly urging the tools in a direction toward the work support, clamp means for securing a work piece in position on the work support, said clamp means including a draw rod and a hydraulic actuator for the draw 15 rod, cam means oscillatable to effect retraction of the tools with respect to the work holder, a hydraulic motor for determining the operation of said cam means, and a hydraulic actuating circuit for said hydraulic actuator and hydraulic motor 20 including timing means for determining the sequential actuations of the respective hydraulic devices.

19. In a machine of the character described including a rotary work support, radially disposed 25 tools disposed in circumscribing relation to the work support, means for yieldingly urging the tools in a direction toward the work support, clamp means for securing a work piece in position on the work support, said clamp means includ- 30 ing a draw rod and a hydraulic actuator for the draw rod, cam means oscillatable to effect retraction of the tools with respect to the work holder, a hydraulic motor for determining the operation of said cam means, a hydraulic act- 35 40 45 uating circuit for said hydraulic actuator and hydraulic motor including timing means for determining the sequential actuations of the respective hydraulic devices, means for supplying coolant to the tools when in operative position, and a hydraulic motor coupled in parallel with the cam control means coupled in series with the cam actuated motor for shutting off the coolant during retracting actuation of the cam.

ALBERT H. DALL.
